UNITED STATES PATENT OFFICE.

JOSEPH GUMBER AND ANTHONY SCHNEIDER, OF EAST MOLINE, ILLINOIS.

CARD-DISPLAY MECHANISM.

1,399,210.

Specification of Letters Patent.

Patented Dec. 6, 1921.

Application filed March 23, 1921. Serial No. 454,621.

To all whom it may concern:

Be it known that we, JOSEPH GUMBER and ANTHONY SCHNEIDER, citizens of the United States, residing at East Moline, in the county of Rock Island and State of Illinois, have invented certain new and useful Improvements in Card-Display Mechanisms, of which the following is a specification, reference being had to the accompanying drawings.

This invention relates to advertising display devices, and particularly to means whereby advertising placards or like matter may be shifted one by one into a display position, held in this display position for a certain length of time, and then removed and a new placard disposed in a display position.

The general object of this present invention is to provide a mechanism of this character which is relatively simple in its construction, which may be relatively cheaply made, which is thoroughly effective for the purpose intended, and which takes but a small amount of electric current or power to operate the machine.

A further object is to provide a mechanism of this character in which a series of placards are supported one behind the other in front of a glazed display opening, the mechanism having power operated means whereby the rearmost card of the series may be lowered to a position below the series of cards, then positively shifted forward and raised so as to be inserted in front of the foremost card of the series, the insertion of a card in front of the series causing the rearmost card of the series to be forced rearward and onto the carrier, which causes the card to be lowered as before stated.

And a further object in this connection is to provide power operated means for positively causing the rearward movement of the last card of the series and its disposition on the carrier and positively preventing the next rearmost card from moving rearward onto the carrier.

Another object is to provide a mechanism of this character in which a vertical reciprocating carrier is used which in its upward movement carries a card upward for insertion into a display position and when it has arrived at its uppermost position receives a card from the rear end of the series or stack of cards and lowers it to a con-

cealed position ready for insertion as the front card of the series.

And another object is to provide positively acting means for operating when a card is lowered to positively shift the card forward and tilt the card so that its upper edge may be inserted in front of the series of cards disposed behind the display opening so that as the carriers rise the card carried by the carrier will be shifted without fail into a display position.

Still another object is to provide a very simple motor operated means for securing the reciprocation of the carrier, the operation of the card shifter fingers and the operation of the escapement mechanism which controls the rearward movement of the cards and permits the last card of the series to be deposited upon the carrier.

Other objects will appear in the course of the following description.

Our invention is illustrated in the accompanying drawings, wherein:

Fig. 1 is a front elevation of our display mechanism with the case removed;

Fig. 2 is an end elevation thereof;

Fig. 3 is a vertical sectional view looking toward one end wall of the mechanism;

Fig. 4 is a vertical sectional view looking toward the other end wall of the mechanism and showing the cards in place and the carrier moving downward;

Fig. 5 is a like view to Fig. 4, but showing the carrier moving upward and inserting a card;

Fig. 6 is a like view to Fig. 5, showing the position of the carrier at the time when the rearmost card is deposited thereon and the card is about to move downward;

Fig. 7 is a fragmentary section on the line 7—7 of Fig. 6;

Fig. 8 is a transverse section through the end wall 11 showing the escapement mechanism in plan view;

Fig. 9 is a like view to Fig. 8 but showing the escapement mechanism shifted;

Fig. 10 is a fragmentary elevation of the mangle rack, the shafts 37 and 44 being in section;

Fig. 11 is a horizontal section of the machine, the casing being removed;

Fig. 12 is a fragmentary elevation of the cam and allied parts for shifting the escapement;

Fig. 13 is a fragmentary sectional per-

spective view of a portion of the carrier; its guide and the side wall;

Fig. 14 is a fragmentary perspective view of one corner of a card and holder therefor.

5 Referring to these drawings, it will be seen that the embodiment of the invention which we have illustrated includes a base 10 which may be formed of a light casting and which is hollow as regards its interior, this 10 base 10 supporting upwardly extending side walls 11 and 11^a of suitable reinforced sheet metal. The base is also provided with lugs 12 whereby a housing 13 (Fig. 6) may be mounted upon the base to entirely inclose the 15 side walls 11 and 11^a and the mechanism disposed between these side walls and carried thereon. The front wall of this housing 13 is formed with an observation opening 14, through which the placards may be observed, 20 this observation opening being covered by a sheet of glazed or other transparent material.

Mounted upon the side walls 11 and 11^a and disposed below the lower margin of this 25 display opening are the oppositely disposed racks—supporting the cards A. These racks are illustrated as formed of short pieces of angle iron 15, the horizontal flanges of which directly support the cards A, these angle 30 irons extending forward and rearward in approximately a horizontal plane. The cards A are supported upon these angle iron racks so that the forwardmost card of the series of cards may be seen through the 35 display opening. The mechanism which we will now describe provides means whereby the rearmost card of the series of cards A may, at regular intervals, be taken from the rear of the series of cards, lowered into position below the series of cards and below the 40 racks, then shifted forward, and then lifted up and inserted between the front of the display opening and the series of cards, this card remaining displayed for a predetermined length of time.

To this end, we have provided the upper pair of pulleys 16 mounted upon the walls 11 and 11^a, a lower forward pair of pulleys 17 mounted at the lower ends of these walls, 50 and certain driving wheels or drums 18 and 19, these driving wheels or drums being mounted upon a shaft 20 which extends longitudinally across the machine. The pulleys 17 may also be mounted upon a common shaft, as may also the pulleys 16, that is there will be a common shaft for the front pulleys and a second shaft for the rear pulleys 16. We do not wish to be limited to this, however, as stub shafts might be used.

55 60 65 Passing over the wheels 16 or pulleys and over the wheels or pulleys 17 are the flexible connections 21 which are preferably made of lengths of chain or cable. The ends of these flexible connections are wrapped to a certain extent around the drums 18 and 19

so that as these drums oscillate by the oscillation of the shaft 20, the cables 21 will be first shifted in one direction and then shifted in the other direction. In the length of each cable there is provided a coiled contractile 70 spring 22 to take up shock and strain when the driving mechanism reverses, and also mounted upon these cables, that is upon the forward stretches thereof, is a carrier bar 23, the opposite ends of which are formed with 75 forks 24 to embrace the vertical guide flanges 25 on the walls 11 and 11^a, this carrier being attached at its ends to the cables 21 and therefore moving therewith. This carrier bar 23 has connected to it the rearwardly 80 projecting tines 26 which are resilient or resiliently connected to the carrier bar. As illustrated, these tines 26 are resilient and are upwardly and rearwardly curved. Collars 27 are mounted on shaft 23 and have 85 rearwardly projecting lugs 28, to which the tines 26 are attached. We do not wish to be limited to this, for, as before remarked, it is sufficient if the tines 26 are either resiliently supported or resilient of themselves. 90

As the cables 21 move in one direction, the carrier bar 23 with its tines 26 is lowered to a predetermined extent and when the direction of motion of the cables is reversed the carrier bar is raised. When the 95 carrier bar is raised, the tines 26 are disposed in a position approximately at the same level as the rear ends of the angle iron racks 15.

The mechanism whereby the shaft 20 is 100 driven and reversed is as follows: Supported on the base of the machine in any suitable manner is a worm gear wheel 29 and engaging therewith is a worm shaft 30. This worm shaft carries upon it a pulley 105 31, which in turn is driven by a belt 32 from a pulley 33 carried by the shaft of the electric motor 34. The worm gear wheel 29 carries a shaft section 35 and this shaft section is flexibly connected by any suitable 110 means to a shaft section 36, which in turn is flexibly connected by a flexible coupling to a shaft section 37 which carries upon its extremity a pinion 38. Mounted upon the drum 19 and preferably forming part of this 115 drum is a mangle rack 39 having external gear teeth 40 and internal gear teeth 41, the rack 39 being interrupted at one point and the external teeth merging into the internal teeth. This gear 39 is formed 120 between the external and internal teeth with an arcuate slot 42. The shaft section 37 is provided with a supporting arm 43 constituting a bearing for the shaft section, this supporting arm being provided 125 with a stud 44 which engages within the slot 42. It will be obvious now that when a rotation is given to the shaft constituted by the sections 35, 36 and 37, the gear wheel 39 will be caused to rotate in one di- 130

rection until the extremity of the gear is reached and that the rotation communicated to the pinion 38 will cause it to pass around the end teeth of the gear wheel, as 5 for instance from the interior teeth 41 to the exterior teeth 40, and that the continued motion of the pinion 38 in one direction will then cause a movement of the gear 39 reversely to the movement communicated 10 to the gear when the pinion was traveling upon the interior teeth 41. The gear 39 will then move in this reverse direction until the stud 44 reaches the opposite end of the slot 42 and the pinion 38 will 15 then travel around the end of the gear teeth from the exterior gear teeth to the interior gear teeth and the gear wheel 39 will be again reversed. Thus a constant rotation of the shaft formed by the sections 20 35, 36 and 37 will cause an intermittent reverse movement of the gear wheel 39, of the shaft 20 and of the winding drums 18 and 19. Thus while the motor and the shaft 25 operated thereby rotate continuously in one direction, the drums will rotate intermittently in opposite directions and the carrier chain or like element 21 will be alternately shifted in opposite directions, alternately lowering and raising the carrier, (see 30 Figs. 4, 5 and 6).

The means which we have just described provides for the raising and lowering of the cards, and the means whereby the rear-most card of the series of cards A supported 35 upon the racks 15 is shifted rearward so as to rest upon the tines 26 is as follows: The walls 11 and 11^a are slotted at 45, and disposed upon the exterior faces of these walls are rock shafts 46, these shafts being mounted 40 in suitable bearings and each shaft having at one end an outwardly projecting arm 47. Each shaft carries upon it an escapement wheel or disk 48 which, as illustrated in Fig. 7, is approximately a segment of a 45 circle and formed to provide the ears 49 and 50 which are deflected with relation to each other so that these ears do not lie in the same plane. When the shaft 46 is rotated to bring the ear 49 behind the last card of the 50 series of cards supported on the racks 15, the ear 50 will be out of engagement with the cards and in a plane in front of the rear-most card of the series. Now when the shaft 46 moves in the opposite direction, the ear 55 49 is withdrawn from behind the last card of the series, while the ear 50 is simultaneously inserted between the last card of the series and the next following card so that this ear 50 acts to positively shift the 60 last card of the series rearward and off of the racks 15. This action is also assisted by the provision of bowed springs 51 which press upon the margins of the cards disposed upon the racks 15 and 65 urge these cards rearward. The escapement 70 mechanism prevents the last card of the series from being shifted off of the racks 15 until the carrier has reached its uppermost position. At this time the shaft 46 is rocked to release the last named card of the series to hold the next rearmost card, and as the carrier descends the shaft 46 is again rocked in a reverse direction so as to insert the lug or ear 49 behind the 75 then rearmost card and the lug 50 is withdrawn from behind this card ready for the next card delivery. This rocking of the shaft 46 is secured by means of cam actuated reciprocating rods 52 carried upon the 80 opposite end walls 11 and 11^a.

The lower ends of these rods are mounted in guides 53 and the upper ends in supporting guides 54. The upper ends of the rods may be reduced, and compression springs 55 will be disposed between the shoulder 85 formed by the reduced portion of the rod and the guides 54, these springs urging the rods 52 downward. Each of these rods carries upon it a collar 56 having an outwardly projecting arm 56^a which is connected by a wrist pin 56^b to the arm 47 of the corresponding shaft 46. Thus as the rods 52 are reciprocated, the shaft 46 will be rocked. The means for reciprocating the rods 52 comprise cams 57, mounted upon the 90 outer extremities of the shaft 20, these cams 57 bearing against tappets 58 adjustably mounted upon the rods 52. As the shaft 20 is rotated, these cams 57 will lift the rods 52, thus oscillating the shafts 46 in one direction, and as the cams 57 leave the tappets 58, the springs 55 will cause the descent of the rods 52 and the oscillation of shaft 46 in the reverse direction. The escapement 100 disks 48 are slidably mounted upon the 105 shaft 46 so that they may be adjusted to accommodate a greater or a smaller number of cards, and the slots 45 are made relatively large for this purpose.

Disposed rearward of the racks 15 and extending upward and rearward from the rear ends of these racks are guides 59 which are angular in cross section and which are each preferably pivoted at one end, as at 60, and adjustably mounted at the other end, as at 110 61, so that these guides may be shifted to accommodate a greater or less number of cards. These guides are downwardly and forwardly curved and engage the upper 115 ends of the cards or sign holders and guide 120 these upper ends downward properly as the card or sign holder descends upon the tines of the carrier.

The descending card rests at its lower 125 edge upon the tines 26, and as the card descends the lower edge of the card would tend to slip downward and forward upon the tines so that the lower edge of the card would be properly positioned at the front of the machine but the upper edge of the card 130

would tend to fall rearward so that the card would be upwardly and rearwardly inclined and upon the upward movement of the carrier could not move into position in front of the series of cards A. We have, therefore, provided positive means whereby the card which has been lowered by the carrier 26 shall be shifted forward and brought flat against the chains 21 and held in this position until the upper edge of the card or of the card holder has been inserted between the first card of the series of cards A and the display opening of the machine. To this end, we have provided a rock shaft 62 having thereon a plurality of upwardly and rearwardly curved fingers 63. This rock shaft is mounted in bearings in the end members 11 and 11^a and carries an arm 64 at one end supported by a collar 65. The shaft section 37 is supported in a sleeve 66, which in turn is carried by an arm 67 on a short stub shaft or pintle 68 so that the sleeve 66 with the shaft section 37 may be shifted laterally to permit the movement of the gear wheel 38 from its engagement with the gear teeth 41 into engagement with the gear teeth 40, or vice versa, and pivoted to this arm 67 is a link 69, which in turn is pivoted to the arm 64 so that as the shaft 68 which carries the arm 67 oscillates, the arm 64 will be oscillated and the shaft 62 will be oscillated, thus oscillating the finger 63. These movements are so timed that when the carrier has reached its uppermost position and the driving mechanism is about to reverse, then upon the reversal of the driving mechanism the arm 67 will be drawn forward, shifting the upper ends of the arms 63 rearward to a position beneath the lower vertically extending ends of the guides 59. Thus as the carrier lowers the rearmost card will rest upon the tines 26 and as the card is lowered the lower edge of the card will be guided forward upon the tines 26 by the downwardly and forwardly inclined or curved arms 63. Thus as the carrier is lowered, the lower edge of the card will be guided toward the front of the machine until, when the carrier is fully lowered, the lower edge of the card will be adjacent to the forks 24. In this position of the parts another reversal of the driving mechanism is had by the pinion 38 coming to the end of its movement on the teeth 41 and the pinion will pass into engagement with the teeth 40, thus reversing the movement of the carrier, as before explained, and also oscillating the shaft 62 in a direction to carry the upper ends of the arms 63 forward, thus tilting the card over against the flanges 25. Then the carrier begins to rise, the card being still held against the flanges 25 until this card is entered between the forward ends of the racks 15 and the flanges 25. The card then continues to move up-

ward until it strikes the spring 51 and wedges itself between this spring and the series of cards. Then when the card has reached its highest position and is in its display position, the escapement disks 48 operate to release the rearmost card, as before explained, and permit its descent. 70

It will be noted that the descent of the card is relatively slow because of the fact that the pinion 38 at this time is traveling upon the outside of the mangle rack, but the ascent of the card is relatively more rapid, due to the fact that the pinion is traveling against the inner teeth 41. While we prefer to use chains to form the elements 21, we do not wish to be limited to this, as small wire cables might be used or any other flexible connections suitable for the purpose required. We do not wish to be limited to the exact formation of the cam 57 or the exact relation of this cam 57 to the rod 52, as another form of cam might be used and the rod 52 might be directly engaged by the cam. The escapement mechanism might also be changed without altering the principle of the invention, as may also the particular manner of driving the mechanism and the general arrangement of the parts. 85

It will be seen that with this device any number of advertising cards within the range of the machine may be intermittently exhibited and that the time period during which they are exhibited may be readily varied by varying the driving speed of the machine. While we do not wish to be limited to this, preferably each card will be disposed within a metallic frame 71, but the particular form of this frame forms no part of our present invention. 95

The general operation of the mechanism is as follows: Assuming that there are a series of cards A resting upon the racks 15 and that the carrier is moving upward, then when the carrier tines 26 reach a position below the rear ends of the racks 15, the pinion 38 has reached the end of the rack or gear teeth 40 and while the pinion is moving around the end of the rack into engagement with the rack teeth 41, the parts are at a relative standstill. Just as the carrier reaches its uppermost position, however, the shaft 20 will carry the cams 57 into position to lift up on the rods 52, raising these rods, and through the arms 57 and 47, the shafts 46 are rocked, which will rock the escapement disks 48 to release the rearmost card of the series and permit the card to be forced rearward off the racks 15 onto the tines 26, the escapement acting at this time, as previously explained, to prevent the undue rearward movement of the remaining cards. The card, when it slips off of the racks 15, drops down onto the tines 26 and the upper edge of the card tilts rearward and rests against the guides 59. During this time the 100

- carrier is approximately at rest and then begins its descent, due to the pinion 38 having engaged with the teeth 40. As the carrier descends the card is carried down and 5 the lower edge of the card shifted forward by means of the fingers 63 and when the carrier has reached its lowest position the shaft 62 is rocked to cause the fingers 63 to tilt the upper edge of the card over and bring 10 the card flat against the flanges 25. By this time the pinion 38 has reached the extremity of its stroke upon the stroke engagement teeth 40 and commences to roll around the end teeth into engagement with the teeth 41. 15 At this time a new card is transferred to the carrier and moves downward, as before stated, is then shifted forward and raised into display position in the manner described. 20 It will be seen that the cards are positively moved under all circumstances. Each card is positively moved rearward and off the ends of the rack. The cards are carried downward and positively moved by the fingers 63 toward the front of the machine and 25 when the card has been fully depressed, the upper portion of the card is positively moved over into position to be carried up into a display position. The cards do not move by gravity except that they follow the tines 26 downward by gravity as the carrier moves downward. All the other movements of the card are positive. A very small electric motor is preferably used for operating the machine, requiring but little current, and it 30 has been found in practice that the cards cannot and do not stick or fail to change at the proper time.

We claim:—

- 40 1. A card display machine including means for supporting a series of cards one behind the other, a vertically reciprocable carrier disposed below the supporting means, means for shifting the rearmost 45 card of the series from the supporting means onto the carrier when the latter is in a raised position, means for lowering the carrier and card and simultaneously shifting the card on the carrier into a position at 50 the front of the carrier and in a plane intersecting the front end of the supporting means, and means for then raising the carrier to a position where the card is in line with the supporting means and then shifting 55 the card rearward onto the supporting means.
2. A card display machine including means for supporting a series of cards one behind the other, a vertically reciprocable 60 carrier having rearwardly and upwardly extending supporting fingers, the carrier being disposed for movement in a plane intersecting the front of the supporting means but below the supporting means, escape- 65 ment mechanism engaging the rearmost card of the series of cards and when actuated permitting the rearmost card to shift rearward but engaging the next rearmost card to hold it from shifting rearward, means for automatically actuating said escapement 70 mechanism when the carrier is in its raised position, and means operating as the carrier descends to automatically shift the card to the front of the carrier, whereby upon the next upward movement of the carrier the 75 card will be inserted in front of the series of cards.
3. A card display mechanism including oppositely disposed racks for supporting a series of cards one behind the other, escapement devices normally holding the cards from rearward movement on the racks, means urging the cards rearward on the racks, a card carrier movable in a vertical plane intersecting the front ends of said supporting racks and having fingers extending rearward and upward below the racks, power operated means for shifting the carrier vertically in opposite directions, means for actuating said escapement means when the carrier has risen to a position with its fingers just beneath the racks to thereby permit the rearmost card of the series to be deposited on the fingers, and means operating automatically when the carrier has descended to 80 positively shift the card carried upon said fingers to the forward ends of the fingers and holding the card in a vertical position while the carrier rises. 85
4. A card display mechanism including oppositely disposed racks for supporting a series of cards one behind the other, escapement devices normally holding the cards from rearward movement on the racks, means urging the cards rearward on the racks, a card carrier movable in a vertical plane intersecting the front ends of said supporting racks and having fingers extending rearward and upward below the racks, power operated means for shifting the carrier vertically in opposite directions, means for actuating said escapement means when the carrier has risen to a position with its fingers just beneath the racks to thereby 90 permit the rearmost card of the series to be deposited on the fingers, a series of upwardly and rearwardly extending fingers oscillatably mounted for common movement on an axis disposed in the plane of the front of the carrier, means for causing the forward movement of the fingers when the carrier has descended to thereby bodily shift the card into a vertical plane coincident with the plane of movement of the carrier, and means for causing the fingers to oscillate 95 rearward when the carrier has moved upward to its fullest extent. 100
5. A card display mechanism including a frame having a display opening, means for supporting a series of advertising cards one 105

- behind the other behind the display opening, a vertically reciprocable carrier mounted for movement in a vertical plane just behind said opening and in front of said supporting means, said carrier having rearwardly and upwardly extending fingers, power operated means for shifting the carrier alternately toward and from the supporting means, means automatically acting when the carrier has reached its uppermost position for releasing the rearmost card of the series of cards and disposing it with its lower edge upon said fingers, and means for gradually shifting the lower edge of the card forward along the carrier fingers as the carrier descends, and then tilting the card into a vertical plane approximately coincident with the plane of movement of the carrier when the carrier has reached its lowermost position.
- 20 6. A card display mechanism including a frame having a display opening and having side walls, supporting racks mounted upon the side walls behind said display opening and supporting a series of cards one behind the other behind the display opening, a vertically reciprocable carrier having rearwardly and upwardly extending tines moving in a vertical plane coincident with the space between the display opening and the forward ends of the racks but below said racks, power operated means for shifting the carrier toward and from the supporting racks, means operated by the power operated means when the carrier has reached its uppermost position releasing the rearmost card of the series of cards and disposing it with its lower edge upon the carrier tines, said means simultaneously preventing the next rearmost card from being discharged upon the carrier, a rock shaft disposed below the lowermost position of the carrier and having a plurality of upwardly and rearwardly extending fingers, means for tilting the rock shaft to carry the fingers to an upwardly and rearwardly extending position intersecting the path of movement of the tines on the carrier when the carrier is in its upward position, and means for rocking the rock shaft reversely to carry the fingers and card on the carrier to a vertical position when the carrier has reached its lowermost position.
7. A card display mechanism of the character described including a frame having a display opening adjacent its upper end and having side walls, oppositely disposed racks supported on the upper ends of the side walls at the lower end of said display opening and behind the same and adapted to support a series of cards one behind the other, springs urging the cards rearward on the racks, escapement devices mounted upon the side walls and adapted when actuated to permit the rearward movement of the rearmost card but prevent the other cards from

moving rearward, a vertically reciprocable carrier mounted for movement in a vertical plane coincident with the forward ends of the racks, power operated means for reciprocating the carrier, said carrier having upwardly and rearwardly extending resilient tines, downwardly and forwardly extending card guides mounted behind the racks, a rock shaft mounted adjacent the path of movement of the carrier and at the lower end of said path of movement and having upwardly and rearwardly extending fingers intersecting said tines, and means acting automatically when the carrier is lowered to shift the rock shaft to carry its fingers toward the path of movement of the carrier and when the carrier is raised to carry its fingers rearward.

8. A card display mechanism of the character described including a frame having a display opening, side walls having inwardly extending flanges, a carrier bar having sliding engagement with said flanges and movable vertically thereon and having upwardly and rearwardly extending fingers, oppositely disposed racks carried by the side walls rearward of the display opening and adapted to support a series of cards thereon, means urging said cards rearward on the racks, downwardly and forwardly extending card guides disposed behind the racks, means for reciprocating the carrier bar toward and from the racks, means acting when the carrier bar has reached its uppermost position releasing the rearmost card of the series of cards and shifting it rearward off of said racks and onto said tines, and means acting automatically when the carrier bar has reached its lowermost position shifting the card into the plane of said carrier bar where by the card will be moved into position in front of said display opening upon the next upward movement of the carrier bar.

9. A card display mechanism including a frame having a display opening and having side walls, racks mounted upon said side walls and adapted to support a series of cards one behind the other and behind the display opening, oppositely disposed flexible connections mounted for movement in opposite directions upon the frame and for movement in a plane behind the display opening, a carrier mounted upon said flexible connections for movement therewith and having rearwardly and upwardly extending fingers disposed below the racks, pulleys supporting said flexible connections, drums to which said flexible connections are attached and by which they are reciprocated, power operated means for rotating said drums alternately in reverse directions, power operated means disposed adjacent the rear ends of the racks for intermittently holding the cards from rearward movement and releasing the last card of the series, said means be-

ing shifted to its released position when the carrier has been raised to a position with its tines beneath the racks to receive a card therefrom, a rock shaft mounted adjacent 5 the front of the frame and below the lowermost position of the carrier and having upwardly and rearwardly extending fingers, means for rotating the rock shaft to tilt the fingers to an upwardly and rearwardly inclined 10 position when the carrier has reached its uppermost position, means for tilting the rock shaft reversely to carry the fingers toward the carrier when the carrier has reached its lowermost position, and card guides disposed behind the racks and adapted to guide the cards onto the carrier tines.

10. In a card display mechanism, oppositely disposed card supporting racks adapted 20 to support a series of cards, one behind the other, means urging the cards rearward on the racks, means for carrying the card discharged from the rear end of the racks into position in front of the racks and inserting it in front of the series of cards thereon, means for permitting the escape of the rearmost card from the racks but preventing the escape of the remaining cards comprising oppositely disposed escapement 30 members having ears relatively deflected to different planes and engageable alternately with the cards, a motor for actuating the card carrying means, and motor actuated means for actuating the escapement members.

11. In a card display mechanism, oppositely disposed card supporting racks adapted to support a series of cards one behind the other, means urging the cards rearward 40 on the racks, means for carrying a card discharged from the rear end of the racks into position in front of the racks and inserting it in front of the series of cards thereon, means for permitting the escape of the rearmost card from the racks but preventing the escape of the remaining cards comprising oppositely disposed escapement disks having ears relatively deflected in different planes and engageable alternately with the 50 cards, a motor for actuating the card carrying means, and motor actuated means for intermittently oscillating said escapement disks.

12. In a card display mechanism, oppositely disposed card supporting racks adapted 55 to support a series of cards one behind the other, means urging the cards rearward on the racks, means for carrying a card discharged from the rear end of the racks into position in front of the racks and inserting it in front of the series of cards thereon, means for permitting the escape of the rearmost card from the racks but preventing the escape of the remaining cards comprising 60 oppositely disposed escapement disks

having ears relatively deflected in different planes and engageable alternately with the cards, a motor for actuating the card carrying means, motor actuated means for intermittently oscillating said escapement disks 70 including a reciprocable rod for each disk, a spring urging said rod downward, a shaft upon which each disk is mounted and operatively connected to the corresponding rod to be oscillated thereby, and a motor driven 75 cam operatively engaging each rod.

13. In a card display mechanism, a supporting frame including end walls, inwardly projecting flanges on the end walls constituting card supporting racks and adapted 80 to support a series of cards one behind the other, means urging said cards rearward on the racks, a vertically reciprocable carrier having rearwardly projecting tines adapted to receive a card from the rear 85 end of the rack and carry said card downward and then upward, means acting when the carrier is lowered to shift the card thereon into a vertical position at the front of the carrier to thereby cause the card to be 90 inserted in front of the series of cards on the racks upon the upward movement of the carrier, motor operated means for reciprocating the carrier and actuating said card shifting means, escapement means for 95 releasing the lowermost card of the series of cards when the carrier is in a raised position but preventing the release of the remaining cards comprising oppositely disposed escapement disks mounted upon the 100 end walls and disposed opposite each other and in a plane parallel to the plane of the cards, each of said disks having relatively off-set lugs having angular relation to each other and adapted to be inserted behind and 105 between the cards alternately, a shaft upon which the disks are mounted and carried upon said walls and each having an arm, a vertically reciprocable rod mounted upon each end wall and having an arm operatively 110 engaging the arm on the shaft, a spring urging each rod downward, a cam for each rod operatively engaging the lower end thereof, and a motor driven shaft upon which the cams are mounted, the cams being set to shift 115 the rods to release a card when the carrier is in its raised position.

14. In a card display mechanism, a supporting frame including end walls, inwardly projecting flanges on the end walls constituting card supporting racks and adapted to support a series of cards one behind the other, means urging said cards rearward on the racks, a vertically reciprocable carrier having rearwardly projecting tines adapted 120 to receive a card from the rear end of the rack and carry said card downward and then upward, means acting when the carrier has lowered to shift the card thereon into a vertical position at the front of the carrier to 125 130

thereby cause the card to be inserted in front of the series of cards on the racks upon the upward movement of the carrier, motor operated means for reciprocating the carrier and actuating said card shifting means, escapement means for releasing the rearmost card of the series of cards when the carrier is in a raised position but preventing the release of the remaining cards, said escapement means being adjustable toward or from the front of the racks to thereby accommodate a greater or smaller number of cards.

15. In a card display mechanism a supporting frame including end walls, inwardly projecting flanges on the end walls constituting card supporting racks and adapted to support a series of cards one behind the other, means urging said cards rearward on the racks, a vertically reciprocable carrier 20 having rearwardly projecting tines adapted to receive a card from the rear end of the rack and carry said card downward and then upward, means acting when the carrier

has lowered to shift the card thereon into a vertical position at the front of the carrier 25 to thereby cause the card to be inserted in front of the series of cards on the racks upon the upward movement of the carrier, motor operated means for reciprocating the carrier and actuating said card shifting means, escapement means for releasing the rearmost card of the series of cards when the carrier is in a raised position but preventing the release of the remaining cards, said escapement means being adjustable toward or from the front of the racks to thereby accommodate a greater or smaller number of cards. 30 35
